INVENTOR.
WESLEY E. WINN
By Arthur L. Slo
ATTORNEY.

UNITED STATES PATENT OFFICE.

WESLEY E. WINN, OF SAN FRANCISCO, CALIFORNIA.

DESIGN FOR A STATUETTE.

Application filed June 3, 1929. Serial No. 31,507. Term of patent 7 years.

To all whom it may concern:

Be it known that I, WESLEY E. WINN, a citizen of the United States, residing in the city and county of San Francisco, State of California, have invented a new, original, and ornamental Design for a Statuette. of which the following is a specification, reference being had to the accompanying drawings, forming a part thereof.

Fig. 1 is a front elevation of a statuette, showing my new design; and

Fig. 2 is a side elevation of the same.

I claim:

The ornamental design for a statuette as shown.

WESLEY E. WINN.
